UNITED STATES PATENT OFFICE.

AUGUSTUS SMITH, OF ROSELLE, NEW JERSEY, ASSIGNOR TO BERGEN POINT IRON WORKS, OF BAYONNE, NEW JERSEY, A CORPORATION OF NEW JERSEY.

DIGGING APPARATUS.

Application filed January 14, 1922. Serial No. 530,497.

To all whom it may concern:

Be it known that I, AUGUSTUS SMITH, a citizen of the United States of America, residing at Roselle, in the county of Union and State of New Jersey, have invented certain new and useful Improvements in Digging Apparatus, of which the following is a specification.

My invention relates to digging apparatus, and particularly to apparatus for operating a digging bucket of the clam-shell or orange-peel type. The invention is concerned particularly with the trolley arrangement by which the bucket is swung from digging to discharge position, and vice versa; and secondly, with the driving machinery or winding drums which control the position of the trolley.

In the accompanying drawings—

Fig. 1 is a side elevation of an installation in which my invention is embodied in one form;

Fig. 2 is a partial elevation at right angles thereto; and

Fig. 3 is a plan of a modified arrangement of the winding drums.

As here shown the digging bucket 1, of the clam-shell type, is suspended by a double line 1'. A one-line bucket may be used if preferred, but a two-line bucket is the more usual type, and either form of suspension may be employed without in any way modifying the present invention. A boom 2 is employed to hold the bucket out at any desired distance from the receiving hopper 3, or other point at which the bucket is discharged. The trolley 4 guides the bucket as it is swung in and out, or toward or from discharge position over the hopper and its outward digging position. The trolley is suspended by a bar rod chain or rope 5 from the outer end of the boom 2, so that when the trolley hangs freely without restraint of its inhaul line, the bucket will hang from the end of the boom in the furthest digging position. The inhaul rope 6 pulls the trolley in and thus moves the bucket to discharge position over the hopper 3.

The inhaul rope 6 is carried over suitable sheaves to a winding drum 7 for operating the trolley inhaul, while the drum or drums 8 operate the bucket, a single drum being used for a one-line bucket, and a pair of

drums frequently mounted on the same shaft 55 being used for a two-line bucket.

The travel of the trolley from digging to discharge position is indicated by the dotted line 9. The path through which the bottom of the bucket swings is indicated by the dotted line 10. If the length of the bucket rope measured from the bucket 1 to the operating drum 8 is the same for any position of the trolley, which results from holding the drum or drums 8 stationary during the operation of in-hauling the trolley, the path 10 of the bucket will be almost equi-distant from the path 9 at almost all points. This is the main object and result of the first phase of my present invention. 70 A further advantage is an elimination of complication in the machinery, and a reduction of weight and cost.

The bucket may be closed and hoisted to a proper distance from the trolley, and the drum or drums 8 then held motionless, while the trolley is pulled in independently by drum 7 pulling on the inhaul rope 6. The simplest form of operating machinery therefore is a means for opening and closing 80 and lifting the bucket by drum or drums 8, and quite independent means for inhauling the trolley by the drum 7. I have devised, however, a combination of drums and their driving gear particularly applicable to my 85 improved form of trolley, the object of which combination is to save one motor and its associated controller, thereby diminishing the cost for a large installation where the expense of the motor and controller 90 would exceed that incident to the arrangement of the gears and brakes to which this phase of invention relates. As here shown, the ropes for opening and closing the bucket are wound on the drums 8 and 8'. 8' is the 95 opening and closing drum operated by its independent motor and loosely mounted on its shaft. 8 is the hoisting or holding drum which may be keyed to the shaft and driven by another motor 11. 12 is a differential or equalizer gear box which when held from rotating by a strong brake applied on the surface 17, will transmit the power of motor 11 through gears 13, 14 and shaft 15, to which gear 14 is keyed, and pinion 16 to 100 the holding or hoisting drum 8. If, however, shaft 15 be held from rotating by the brake 20, and the brake on surface 17 be

released, the motor 11 will cause the differential or equalizer casing 12 to revolve, and with it pinion 18 keyed to the outside of the casing, which in turn will drive the gear 19 and turn the drum 7 on which the inhaul rope connected to the trolley is wound.

The geometrical properties of my improved apparatus are such that drum 8 may stand still while drum 7 is revolved, and vice versa, which is readily accomplished by the arrangement of gears and brakes I have described.

If an operator of some experience and skill should desire to rotate drum 7 before he stops drum 8, and thus cause the trolley to swing in while the bucket is still rising, which would cause the bucket to travel in a curved path becoming at last tangent to the curved path marked 10 in Fig. 1, he could do this by allowing brake on surface 17 to slip a little which would permit drum 7 to revolve slightly without entirely stopping the shaft 15 and drum 8. Such a proceeding, while requiring considerable manipulating skill, would reduce the time of a trip of the bucket from loading to discharging position slightly and with no unreasonable use of the machinery because by the arrangement of ropes shown in Fig. 1 it will be noticed that the pull of rope 6 which in hauls the trolley is always opposed to the pull of the rope from the bucket to drum 8, and hence as the bucket is pulled in over the receiving hopper the resistance of drum 7 to being revolved by the motor constantly increases until, at some point in the path, it would exactly balance the resisting

torque of drum 8 and thus tend to relieve the brake on surface 17 and brake 20, even if the apparatus were used in the simple way of hoisting the bucket first and then in hauling the trolley. A further useful property of the relation of gears and drums shown is that the motor 11 will continue to revolve in the same direction without pause, whether hoisting the bucket or in hauling the trolley, which is what is required in Fig. 1. On the return trip the motor 11 will revolve in the same direction to unwind drum 7 and let the trolley swing out, and then to unwind drum 8 and allow the bucket to fall, whether the operation be successively performed or combined to some extent by permitting a slight slippage on the brake 17 as on the up trip, described previously.

Various modifications in details of arrangement and construction of parts will readily occur to those skilled in the art, without departing from what I claim as my invention.

I claim:

In apparatus of the type described, a tower, a boom thereon, a pendulum trolley suspended from the outer end of the boom, a sheave on the boom, a bucket operating rope engaging said pendulum trolley and boom sheave, a sheave on the tower, inhaul rope means extending directly from the pendulum trolley to the tower sheave, and means for operating the trolley inhaul and the bucket operating ropes.

In testimony whereof I have signed my name to this specification.

AUGUSTUS SMITH.
